UNITED STATES PATENT OFFICE

138,900

DESIGN FOR A WIRE STITCHING MACHINE

Roy G. Hoffert, Racine, Wis.

Application June 14, 1944, Serial No. 113,989

Term of patent 14 years

(Cl. D55—1)

To all whom it may concern:

Be it known that I, Roy G. Hoffert, a citizen of the United States and a resident of Racine, in the county of Racine and State of Wisconsin, have invented a new, original, and ornamental Design for a Wire Stitching Machine, of which the following is a specification, reference being had to the accompanying drawings, forming part thereof, in which:

Fig. 1 is a front elevational view of a wire stitching machine showing my new design;

Fig. 2 is a transverse sectional view on the line 2—2 in Fig. 1;

Fig. 3 is a side elevational view of my new design looking toward the left in Fig. 1;

Fig. 4 is a side elevational view of the same looking toward the right in Fig. 1;

Fig. 5 is a transverse sectional view taken on the line 5—5 in Fig. 4; and

Fig. 6 is a rear elevational view of my new design.

The dominant features of my design reside in the portions shown in full lines.

I claim:

The ornamental design for a wire stitching machine, substantially as shown and described.

ROY G. HOFFERT.
